UNITED STATES PATENT OFFICE

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN

AIRSHIP

Application filed June 19, 1929. Serial No. 371,987.

This invention relates to airships, and more particularly to the organization and mounting of the elements comprising an airship.

5 An object of my invention is to provide a rugged light weight aeroplane capable of developing a high rate of speed.

Another object of my invention is to provide an aeroplane structure in which the usual supporting frame is eliminated.

10 Another object of my invention is to provide an aeroplane in which the power plant serves as the supporting member for the other elements.

15 Another object of my invention is to provide an aeroplane in which the fuselage is attached to and entirely supported by the power plant.

20 Still another object of my invention is to provide an aeroplane in which the wing structure and associated elements are supported by the power plant.

25 A further object of the invention is to provide an aeroplane in which the landing gear is attached to the power plant.

Other objects of the invention will appear from the following description taken in connection with the drawings which form a part of this specification, and in which:

30 Fig. 1 is a front elevation of an aeroplane constructed in accordance with the invention;

Fig. 2 is a side elevation of the front portion of the aeroplane;

35 Fig. 3 is a top plan view of the aeroplane;

Fig. 4 is an enlarged plan view of a fragmentary portion of the same;

Fig. 5 is a vertical sectional view of one of the cylinders of the engine.

40 In the drawings, 10 represents generally the power plant of an aeroplane which in this instance is preferably of the radial type consisting of four banks of nine longitudinally aligned cylinders 11 and a central crank case

45 12 through which the crank shaft 13 extends. A propeller 14 is secured to the forwardly projecting end of the crank shaft, or if desired it may be geared to be driven by the crank shaft.

50 The power plant illustrated is of the four-

cycle Diesel type, however, other kinds of aeroplane engines can be used if desired, and a radial type is not requisite, however, it is desirable in that the overall dimensions for a plurality of cylinders is the minimum with

55 the radial engine. A piston 15 is arranged to reciprocate in each cylinder, and the pistons are connected with the crank shaft by the connecting rods 16. The cylinder heads

17 are provided with a single port 18 extending therethrough for the intake of air and the exhaust of burnt gases, suitable valves

19 controlling such ports and being actuated by rock levers 20 arranged in housings 21 as

50 associated with the cylinder heads. Such rock levers are actuated by the rods 22 reciprocated through suitable mechanism driven from the crank shaft.

Liquid fuel injection devices, each consisting of a nozzle section 23 and a pump section 24, are associated to spray

55 liquid fuel into the air charges compressed in the cylinder, such devices being actuated by rods 25 driven through suitable mechanism from the crank shaft.

It will be understood that the air and fuel are introduced

50 into the working chambers in the cylinders where they are mixed to form a combustion

55 charge which is ignited by the heat of compression, or other ignition means if desired.

For further details of the operation of the

60 engine herein illustrated, attention is directed to my co-pending application Serial No.

65 358,899 filed April 29, 1929.

The power plant is utilized to serve as the

70 support for all other elements comprising

75 the aeroplane, and thereby eliminating the

usual frame employed for this purpose. The

70 rear end of the crank case is formed with an

out-turned annular flange 26 to which the

75 annular ring 27, at the front end of the fuse-

80 lage 28, is secured by the bolts 29. The fuse-

85 lage illustrated, other than the attaching

80 ring described, is of the conventional design

85 and a description thereof is not thought to be

90 necessary to an understanding of the invention.

95 It may be interesting to note, however, that suitable frame work extends rearwardly from the ring which is fastened to the engine.

The landing gear is also attached to and

100 supported entirely by the power plant. To

this end I form two of the heads of the cylinders 11 with brackets 30, the lower ends of which the bifurcated leg of the struts 31 are secured to by the bolts 32. The struts 31 are 5 of V-form the rear leg being secured to the circular rear flange 26 of the engine by bolts 33, and the junction portion of the struts provide hubs 34 for carrying the axle 35 upon which is carried the wheels 36.

10 The wings, with their associated elements, are attached directly to and supported by the power plant. The wings are indicated at 37, and except for the mounting features they are of the type usually employed with mono- 15 planes. The ends of the wing's structures, adjacent the engine, are bifurcated and fastened to a projecting bracket 38, formed with two of the cylinder heads, by the bolts 39 or other suitable fastening means. Wires 40 20 and 41 are provided to support the outer end of the wings, the wire 40 being secured to brackets 42 formed on two of the upper cylinder heads, while the other end of such wires is fastened to the outer end of the wing, 25 turnbuckles 43 being provided to create the desired tension. The wires 41 are secured at one end to flanges 44 extending from the nuts securing the landing wheels upon the axle, and the other ends are secured to the 30 outer end of the wings, turnbuckles 45 being employed to place such wires under the desired tension. The rear portion of the wings are supported from the engine by the V-shaped struts 46, the ends of which are secured 35 to the ring 26 of the engine by the bolts 47 and 33. The struts have a hub portion 48 which is secured to the bifurcated portion 49 of the wing structure by the bolts 50.

40 The cylinders extend into the crank case and are secured rigidly therewith by the circular compression rings 51, such securing means being the subject matter of my co-pending application, Serial No. 287,963, filed 45 June 25, 1928.

It will be seen that I have provided a skeleton aeroplane structure having an engine capable of developing high horse power, and that, with the manner of attaching the elements, results in a very light weight high speed structure. Thus, in addition to simplifying the structure, a higher rate of speed can be developed through reduction in weight 50 per horse power developed by the engine.

55 Various changes in the details of attachment of the elements comprising the aeroplane illustrated and described can be made without departing from the spirit of the invention and the scope of what I claim.

What I claim is:

1. In an aeroplane, an engine and fuselage, said fuselage being attached to and entirely carried by said engine.
- 65 2. In an aeroplane, an engine and wings,

said wings being carried entirely by said engine.

3. A skeleton aeroplane for developing high speeds comprising an engine, landing gear, wings and fuselage, said gear, wings and fuselage being carried entirely by the engine. 70

4. In an aeroplane, an engine, wing structures attached to the engine, and wing control wires carried by the engine and extending to the wings. 75

5. In an aeroplane, an engine having a plurality of cylinders, and landing gear supported directly from some of said cylinders.

6. In an aeroplane, an engine structure including a plurality of cylinders and cylinder heads, and landing gear supported from some of the cylinder heads. 80

7. In an aeroplane, an engine structure including a plurality of cylinders and cylinder heads, some of said heads having brackets projecting therefrom, and landing gear supported from the cylinder head brackets. 85

8. In an aeroplane, an engine structure including a plurality of cylinders and cylinder heads, some of said heads having projecting brackets, struts secured to said brackets, and landing gear secured to said struts. 90

9. In an aeroplane, an engine structure including a crank case and cylinders, and landing gear supported partly by the crank case and partly by some of the cylinders. 95

10. In an aeroplane, an engine structure including a crank case and cylinders, struts, some of said struts being secured to some of the cylinders and other of said struts being secured to the crank case, and landing gear carried by the struts. 100

11. In an aeroplane, an engine structure including cylinders and cylinder heads, and wing structures secured to some of the cylinder heads. 105

12. In an aeroplane, an engine structure including cylinders, and wing structures secured to some of said cylinders. 110

13. In an aeroplane, an engine structure including cylinders and cylinder heads, brackets extending from some of the cylinder heads, and wing structures secured to said brackets. 115

14. In an aeroplane, an engine structure including cylinders and a crank case, wing structures, and connecting means between the wing structures and said cylinders and said crank case. 120

15. In an aeroplane, an engine, and a fuselage secured integrally to one end of the engine, a wing structure partly secured directly to the engine, and fastening means for the wing structure extending through a portion of the fuselage and engaging the engine. 125

16. In an aeroplane, a radial engine including a crank case and cylinders, a fuselage secured directly to the rear end of the crank case, landing gear including struts secured 130

directly to said cylinders and crank case, and wings secured directly to said cylinder and crank case.

17. In an aeroplane, a multi-bank radial engine including cylinders and a crank case, wings attached directly to certain heads of said cylinders, and wing control wires carried directly by certain of the heads of said cylinders.

10 In testimony whereof I affix my signature.

LIONEL M. WOOLSON.
